UNITED STATES PATENT OFFICE.

MARCUS T. LOTHROP, OF CANTON, OHIO, ASSIGNOR TO THE TIMKEN ROLLER BEARING COMPANY, OF CANTON, OHIO, A CORPORATION OF OHIO.

APPARATUS FOR SIZING AND QUENCHING CUPS AND CONES.

Application filed March 22, 1920. Serial No. 367,897.

To all whom it may concern:

Be it known that I, MARCUS T. LOTHROP, a citizen of the United States, and a resident of the city of Canton, in the county of Stark and State of Ohio, have invented a new and useful Improvement in Apparatus for Sizing and Quenching Cups and Cones, of which the following is a specification.

My invention relates to devices and processes for sizing and quenching cups and cones for roller bearings and the like and has for its principal object to minimize or dispense wholly with the operation of grinding the bearing surface. It consists principally in means hereinafter described for preventing distortion during the quenching operation; it also consists in supporting the cup or cone during the quenching operation in such manner as to maintain the proper concentricity thereof; it also consists in means for insuring the desired size and taper of the cup; and it also consists in the process and in the parts and combinations and arrangements of parts hereinafter described and claimed.

In the accompanying drawing wherein like numerals refer to like parts wherever they occur,

Fig. 1 is an end elevation of a sizing and quenching machine embodying my invention;

Fig. 2 is a front elevation of the machine; Fig. 3 is an enlarged vertical section through the quenching and cup expanding device, one of the expanding plugs being shown in its lowermost position and in engagement with a cup and the other of said plugs being shown in its uppermost position and after a cup has been stripped therefrom;

Fig. 4 is a vertical section on the line 4—4 in Fig. 1, showing the mechanism for operating the clutch and the mechanism for locking the cam shaft;

Fig. 5 is a fragmentary end view of the parts shown in Fig. 4;

Fig. 6 is an enlarged vertical section taken through the lower end portion of one of the expanding plugs; and

Fig. 7 is a view of the lower end of the plug.

The cup of a conical roller bearing is a hollow ring or shell whose inner surface is a bearing surface and has to be finished as precisely as practicable to a true cone. The

outer surface may be either conical or cylindrical but is concentric with the inner surface. The usual process of manufacturing these cups calls for careful machining, after which they are submitted to the heat treatment necessary to harden the inner bearing surface thereof. Heretofore the operation of hardening the cups has usually resulted in more or less distortion of the work that necessitates grinding of the bearing surface, followed by a finishing operation such as burnishing. The grinding operation is not only expensive but it is injurious to the product in that it removes more or less of the hardened shell thereof. Besides, much of the product is distorted beyond redemption or is so inaccurate as to diameter or taper that it has to be scrapped.

Numerous efforts have been made to overcome the tendency to distortion; but so far as I know, the proposed devices have been quite inefficient for the purpose.

The sizing and quenching machine shown in the drawings comprise a table 1 supported on suitable standards 2. Mounted in a pan or receptacle 3 near one end of the table at the front thereof is a pair of spaced combined cup holders and quenching devices 4. Each of these quenching devices comprises a top annular member 5, an intermediate circular plate 6 and a bottom circular plate 7, all of which are preferably secured together by means of a circular series of bolts 8, which are located near the outer edge of the holder.

According to my invention, the cup is made and handled in the usual way until the close of the heat treatment except that it is made with a bore of slightly less diameter than is required for the finished cup. The hot cups 9, as they come from the furnace, are placed on a circular supporting plate 10, which is located in a central circular depression formed in the upper surface of the intermediate plate 6 of each of the cup holders. Each plate 10 is provided at its outer edge with an upwardly projecting flange 11, which tends to roughly center the cup when placed in position thereon. The holders are spaced the desired distance above the table by means of removable spacing blocks 12. The intermediate plate 6, the bottom plate 7 and the spacing block 12 of each holder and the table 1 are all provided

with central vertical openings which are disposed in axial alinement.

The quenching liquid is conducted to the cup holders from a main supply pipe 13 provided with a control valve 14. The supply pipe 13 has oppositely extending horizontal branches 15 whose outer ends extend upwardly in axial alinement with the central openings in the cup holders 4. The upper end of each branch pipe 15 is provided with a valve 16 provided with a ball-check 17, the purpose of which will herein-after be described. Communication is established between the respective valves 16 by means of a horizontally disposed pipe 18. Communication is established between the cup holders 4 and their respective branch pipes 15 by means of vertically disposed pipes 19. The pipes 19 extend through the aligned openings in the table 1 and spacing blocks 12 and are threaded into the central openings in the bottom plates 7 of the holders, their upper ends terminating flush with the upper surface of the bottom plates. The lower ends of the pipes 19 are threaded in the upper ends of the valves 16, thus establishing communication between the main supply pipe 13 and each of the holders. A nut 20 is threaded on the lower end of each of the pipes 19 and bears against the bottom surface of the table to hold the pipes in position.

The intermediate plates 6 of the holders are provided with a series of radially spaced horizontally disposed ports 21 whose inner ends communicate with the upper ends of the pipes 19 and whose outer ends communicate with a circular series of vertical ports 22, which are formed by aligned vertical holes in the intermediate plates 6 and the annular top plates 5 of the holders. The flow of the quenching liquid from the ports 21 and 22 into the central openings in the annular top plates 5 of the holders is accomplished by means of a series of horizontally disposed jet openings 23, which lead from the vertical ports 22 to the central openings in the holders.

The valves 16 in the branch pipes 15 are opened and closed by means of valve rods 24 arranged in the pipes 19. These valve rods are arranged for vertical movement in the pipes 19 and provided with oppositely projecting pins or lugs 25, which engage the inner walls of the pipes 19 and thus center the valve rods therein. The lower ends of the valve rods are provided with beveled head portions 26 which seat against beveled valve seats formed in the valves 16. The beveled heads of the valve rods are normally retained against the valve seats by the pressure of the quenching liquid on the under sides of the head portions of the valve rods, thus stopping the flow of the quenching liquid from the main supply pipe to the cup

holders. The holders are provided with a series of radially spaced drain openings 27, which permit liquid in the central openings of the cup holders to drain into the pan 3. These openings are in the form of radial grooves cut in the under side of the top members 5 of the cup holders. The pan 3 is provided with a drain pipe 28 for carrying away the quenching liquid which drains into the pan from the cup holders. This drain pipe 28 extends upwardly through the table 1 and pan 3, its upper edge terminating flush with the bottom of said pan. The horizontal pipe 18 which connects the two valves 16 of the branch pipes 15, is also connected to the waste pipe 28 by means of a pipe 29. The purpose of this connection will be hereinafter described.

The hot cups 9, after being placed on the plates 10 of the holders, are engaged by vertically movable tapered plugs 30, which are located above the holders in axial alinement therewith and are adapted to expand said cups. These expanding plugs are adjustably mounted on the lower ends of vertically movable slide rods 31 and have conical lower end portions 30a of the same taper as that desired for the inner surfaces of the finished cups. The slide rods 31 are slidably mounted in bearings 32 secured to the horizontal member of an open frame 33, which projects upwardly from the table, and are alternately actuated in a manner hereinafter described. The expanding plugs have threaded upper end portions 34 which are screwed into the slide bars 31, and are provided with lock-nuts 35 for locking them in the desired positions of adjustment. Accordingly, the stroke of the plugs can be so adjusted or limited that the portion thereof of the size desired for the cup shall be in contact with the cups at the lower limit of the stroke of each of said plugs.

Devices for stripping the cups from the tapered ends of the expanding plugs 30 when the plugs are in their uppermost positions are mounted on their lower end portions. These devices comprise cylindrical sleeves 36 which are loosely sleeved on the lower ends of the plugs and are held thereon by means of pins 37. These pins extend through horizontal holes in the expanding plugs, fitting tightly therein. The opposite ends of the pins 37 extend into elongated vertical slots 38 formed in the stripping sleeves 36. The stripping sleeves have nuts 39 threaded on their upper ends, the nuts being provided with oppositely disposed set-screws for locking them to the stripper sleeves in any desired position of adjustment. With this arrangement, when the plugs reach their uppermost positions, the adjusting nuts 39 on the upper ends of the stripping sleeves 36 strike the lower ends of the bearings 32 of the slide rods 31 and

are held stationary. Whereupon, further movement of the plugs causes the cups to engage the stripper sleeves and be forced off the tapered ends of the plugs.

5 The lower ends of the expanding plugs 30 have central bores which extend upwardly from their bottom faces and form cylindrical chambers 40 therein. Studs 41 are threaded into the upper ends of the chambers 40, the studs being of smaller diameter than that of the chambers to leave a space between the studs and the walls of said chambers. The head portions of the studs are adapted to engage the upper ends of 15 the valve rods 24 for actuating the same and said studs are provided with lock-nuts 42 for clamping them in the desired adjusted position.

As illustrated in Fig. 6, the tapered surfaces 30^a of the expanding plugs 30 are fluted as at 43, the flutes being preferably inclined from the vertical. The plugs are provided with a series of horizontally disposed radially spaced ports 44, which lead 25 from the bottom of the flutes to the chambers 40 in the lower ends of said plugs. These chambers, in turn, communicate with the branch pipes 15 through circular openings in the cup supporting plates 10, and 30 the intermediate plate 6 of the cup holders. Thus, with this arrangement, when one or the other of the plugs is forced axially into a hot cup, the taper of the inner surface of the cup is maintained or becomes the same 35 as the taper of the plug and the inside diameter of the cup will be increased more or less according to the distance the plug is forced into the cup. The action of forcing the plugs into the cups causes the stud 40 screws 41 on their lower ends of the plugs to engage the upper ends of the valve rods 24, thus forcing the engaged valve rods 45 downwardly and forcing their tapered head portions off the beveled valve seats in the valve 16. This opening of the valves permits the quenching liquid to flow from the branch pipes through the valves and thence upwardly through the pipes 19 into the circular openings in the intermediate plate 6 50 of the holders. Part of the quenching liquid flows through the horizontal ports 21 in the intermediate plate 6 in the holder and enters the vertical ports 22 which connect therewith, and is forced through the jet 55 openings 23 against the outer surface of the cup. The liquid is also forced upwardly through the central opening in the intermediate plate 6 and the central opening in the cup supporting plate 10 into the hollow 60 chamber 40 in the lower end of the plug. The liquid is then forced through the horizontal ports 44, which lead from the hollow chamber 40 of the plug to the bottom of the flutes 43 formed in the outer surface thereof, and is directed against the inner surface

of the cup. The annular flange 11 of each cup supporting plate 10 is provided with a series of vertical notches which permit the quenching liquid to drain off the cup supporting plate into the circular opening in 70 the top of the holder. When the expanding plugs are raised, the cups cling to their tapered ends and are stripped therefrom in the previously described manner. When the valves are opened, and the liquid is being directed against the inner and outer surfaces of the cup, the liquid which accumulates in the central opening in the holders drains into the pan 3 through the series of drain openings 27 in the top members 5 of 80 said holders. The liquid in the pan is then carried away by means of a waste pipe 28. This raising of the plungers or plugs 30 also releases the valve rods 24 and the pressure of the liquid on the lower ends of the 85 valve rods forces the beveled heads of the valve rods against their tapered valve seats, thus closing the valves 16 and stopping the flow of liquid to the quenching devices 4. After the valves 16 have been closed, the 90 quenching liquid standing in the cup holders and in the pipes 19 flows through the horizontal pipe 18, which connects the valves and thence through the pipe 29 into the waste pipe 28. The pressure of the 95 waste water is so slight that the liquid passes around the ball-checks 17 without forcing the same against its seat to close the pipe 18. When the valves 16 are open to permit the liquid to enter the cup holders, the flow of liquid through the valves forces the ball-checks 17 against their seats, thus closing the pipe 18 and preventing flow 100 of liquid from the supply pipe 13 into the drain pipe 28. It is noted that the liquid 105 supply system will operate successfully without the use of ball-checks but with a greater waste of quenching liquid.

The slide bars 31, to which the expanding plugs 30 are secured, are simultaneously 110 raised and lowered by means of a duplex toggle so that one bar is in its uppermost position and the other bar is in its lowermost position at the end of their movement. This toggle comprises a pair of upper links 115 46 and a pair of lower links 47, the adjacent ends of the upper and lower links of each toggle being pivotally secured together; and the lower ends of the lowermost links are pivotally connected with the upper 120 ends of the slide rods 31. The upper ends of the upper links 46 of each toggle are pivotally secured to a cross-bar of the frame 33 by means of anchor brackets 46^a. The upper and lower links of each toggle are 125 connected at their point of junction by means of a connecting link 48. Power is applied to the points of junction for bending and straightening the toggle links by means of a horizontally moving yoke. This 130

yoke comprises horizontally disposed spaced parallel slide rods 49 whose opposite ends are connected by means of vertically disposed cross-arms 50. The slide bars 49 of the yokes are slidably mounted in bearings 51, which are bolted or otherwise secured to the open frame 33.

This yoke is alternately shifted in opposite horizontal directions by means of a cam 52 which is fixed to the outer end of a horizontally disposed cam shaft 53. This cam shaft 53 is journaled in bearings 54 formed thereto in the open frame. The cross-bar 50 of the yoke located nearest the double toggle is connected to one end of a horizontally disposed slide bar 55 which works in the bearing 55 secured to the side of the open frame. The other end of this slide bar is connected to the links of the nearest toggle at their point of junction by means of a link 56. The cam 52 on the cam shaft 53 is located between the cross-bars 50 of the yoke. Each of these cross-bars has a cam roller 57 journaled therein. One of the cam rollers is engaged by the peripheral edge of the cam plate 52 during each half revolution of the cam shaft, thus alternately sliding the yoke in two opposite horizontal directions during each revolution of the cam shaft. This movement of the yoke, by reason of its connection with the duplex toggle, causes the toggle links to alternately bend and straighten and the expanding plugs to be alternately raised and lowered.

The cam shaft 53 is driven from a horizontally disposed drive shaft 58 journaled in bearings 59 secured to the table 1 of the machine. This drive shaft is provided at its outer end with a drive pulley 60 and has a drive pinion 61 secured thereto. This drive pinion meshes with a gear 62 which is rotatably mounted on a parallel counter shaft 63 located beneath the cam shaft 53 in vertical alignment therewith. One end of this counter shaft is journaled in a bearing 64 secured to the table and its opposite end portion is journaled in spaced upright side members 33^a of the open frame 33. A small gear 65 is keyed to the counter shaft 63 and is located between the side members 33^a of the frame. This gear meshes constantly with a large gear 66 fixed to the cam shaft 53. The large gear 62 of the counter shaft is constantly driven by the drive pinion 61 on the constantly rotating drive shaft 58, but no movement is imparted to the counter shaft 63 by reason of the loose mounting of said large gear 62 thereon. The end portion of this large gear 62 is provided at one end with clutch jaws 67 adapted to be engaged by smaller clutch jaws 68 formed on the adjacent end of a slideable clutch member 69. This clutch member is splined on the counter shaft 63 to rotate with the same when the clutch is

thrown into engagement with the constantly rotating gear 62. This forms a double reduction drive gearing for the cam shaft.

The sliding clutch member 69 on the counter shaft 63 is normally held out of engagement with the constantly rotating gear 62 on said counter shaft by means of a vertically disposed lock rod 70, which is slidably mounted in a bearing 71 bolted to the frame 33. This lock rod is located directly above the sliding clutch 69 and is provided at its upper end with a weight 72 which normally holds its lower end in contact with the cylindrical surface of said clutch. The lower end of the lock rod 70 has a cam roller 73 journaled thereon whose cylindrical surface is adapted to be engaged by the adjacent beveled side edge of a cam lug 74 formed on the cylindrical surface of the clutch 69. The end of the clutch, adjacent to one of the upright members 33^a of the frame 33 is provided with a series of cylindrical bores in which are mounted studs 75. The inner end portions of these studs are reduced and have springs 76 sleeved thereon, the opposite ends of said springs bearing against the respective inner ends of the bores and the shoulders formed by the reduced portions of the studs 75. These studs bear against a hardened circular disk 77 located between the adjacent upright frame member 33^a and the adjacent end of the clutch 69. Thus, the studs mounted in the clutch member are pressed against the disk 77 and tend to force the clutch into engagement with the gear 62 and couple said clutch and said gear together. The clutch is held out of engagement with the gear 62 by the lock rod 70, the cam lug 74 of the clutch bearing against the cam roller 73 on the lower end of said lock rod. When the lock rod 70 is lifted from its position in front of the cam lug 74, this action permits the spring pressed studs 75 to force the clutch into engagement with the gear 62. This causes the cam lug 74 to move into a position beneath the lower end of the lock rod and, during the rotation of the clutch, the cam lug travels beyond the lower end of the lock rod and thus permits the lower end of the rod to engage the cylindrical surface of the clutch. Continued rotation of the clutch causes the cam lug to rotate with the clutch and to be brought around into a position which permits its beveled edge to engage the cam roller on the lock rod, which action slides the clutch a sufficient distance along the shaft to uncouple said clutch from the constantly rotating gear 62.

The clutch 69 is uncoupled from the rotating gear 62 during every complete revolution thereof and is always stopped with its cam lug in position behind the lock rod 70 by means of a spring pressed stop pawl 78 and a stop disk 79. The stop disk 79 is

fixed to the cam shaft 53 and its peripheral edge is provided with two oppositely disposed notches 80 which are spaced apart 180 degrees. The stop pawl 78 is pivoted to the frame 33 and is provided with a catch at one end which normally engages one of the notches and prevents rotation of the cam shaft in its direction of rotation. The notches 80 formed in the stop plate 79 are shaped after the manner of ratchet teeth whereby when the latch end of the pawl 78 is lifted out of one of the notches, the cam shaft is permitted to rotate 180 degrees before it is again stopped by the action of the pawl engaging the other notch when said notch reaches a position beneath the latch end of the pawl.

The pawl 78 is withdrawn from engagement with the notches in the stop disk to permit the cam shaft to rotate, and the stop rod 70 is lifted from its position in front of the cam lug 74 on the clutch 69 to permit the clutch to be coupled with the gear 62, by means of a vertically disposed latch rod 81. This latch rod is made in two sections, the upper section being connected to the pawl 78, and the adjacent ends of the upper and lower sections of the latch rod have a slot and pin connection with one

arm of a horizontally disposed yoke lever 82. The opposite end of the yoke lever 82 is bifurcated to embrace the lock rod 70 and is located beneath the weight 72 on the upper end of said lock rod. This yoke lever is fulcrumed on a pin mounted in spaced lugs 83 which project upwardly from the bearing 71 in which the lock rod is slidably mounted. The adjacent ends of the upper and lower sections of the latch rod are secured together by means of a pin 84 which extends through a slot 85 in the adjacent end of the yoke lever 82. Thus, when the latch rod is raised, the slot 85 permits the latch rod to be raised and lift the pawl 78 out of the notches of the stop disk 79 before the yoke is actuated to lift the lock rod 70. The latch rod is normally held in its uppermost position to lock the cam shaft 53 and to hold the clutch 69 in its uncoupled position by means of a coil spring 86. This spring is sleeved on the lower section of the latch rod. The lower end portion of the latch rod extends through a hole in the table of the machine. The lower end of the spring 86 rests on the table and its upper end bears against the underside of a collar 87, which is secured to the latch rod, thus normally holding the latch rod in elevated position.

The latch rod is depressed to release the cam shaft 53 and the clutch 69 by means of a horizontally disposed foot lever 88. The middle portion of this lever is pivoted to the middle one of the standards 2 which support the table 1. The forward end of the foot lever 88 is provided with a foot pedal por-

tion and its rear end is connected to one end of a horizontal lever 89 by means of a vertical link 90. The middle portion of the lever 89 is fulcrumed in a bracket 91, which is secured to the under side of the table, and its other end is pivotally connected to the lower end of the latch rod 81.

Assuming the parts to be in their positions of rest, the operation of the machine is as follows: The hot cup as it comes from the hardening furnace is placed in one of the cup holding and quenching devices 4 beneath a raised expanding plug 30. The operator then depresses the forward end of the foot lever 88, thus raising its rear end, which is connected to the inner end of the lever 89 by means of the link 90. This forces the inner arm of the lever 89 upwardly and causes its outer arm, which is connected to the lower end of the latch rod, to swing downwardly and pull down the latch rod 81. This downward movement of the latch rod lifts the latch end of the pawl 78 from out of engagement with the notch 80 in the stop disk 79, thus unlocking the cam shaft 53. Further movement of the latch rod actuates the yoke lever 82, causing its bifurcated end portion to engage the weight 72 on the lock rod 70, thus raising the same from its position in front of the cam lug 74 of the clutch member 69. This unlocking of the clutch permits the spring pressed pins 75 to slide the clutch along the counter shaft 63 and force said clutch into engagement with the constantly driven gear 62 on said counter shaft.

This gear 62 is driven from the drive shaft 58 at a reduced speed by means of the smaller drive gear 61, preferably at the ratio of 2 to 1. The pinion gear 65 on the counter shaft drives the larger gear 66 on the cam shaft at a reduced speed, the ratio also being 2 to 1. The rotation of the cam shaft causes the cam 52 fixed to its forward end to engage the cam rollers 57 of the yoke, thus sliding the same in a horizontal direction. This sliding of the yoke in either direction, by reason of its connection with the double toggle links, straightens one set and breaks the other. This action causes the expanding plug 30 of the straightened toggle link to move downwardly and engage the cup mounted on the holder located below, thus expanding the cup to the desired diameter. This downward movement of the expanding plug also depresses the valve rod 24, thus opening the valve 16 and permitting a stream of quenching liquid to be directed against the exterior and interior surfaces of the engaged cup. Thus, while the parts are thus assembled, and preferably while the pressure on the inner plug is still maintained, they are submerged in the quenching liquid. During this action, the toggle link whose joint has been broken,

6
raises the other of the expanding plugs, thus releasing the valve rod 24 operated thereby and cutting off the flow of quenching liquid to the quenching device in which said plug 5 works. This upward movement of the expanding plug causes the stripper sleeve 36 to strike the under side of the cross-arm of the frame, thus causing the cup to engage the lower end of the stripper and be forced 10 off the tapered end of said plug. On account of the taper of the plug, the quenched cup can be stripped therefrom without injuring the inner surface thereof. The cup is then removed and the new cup is placed in 15 position beneath the raised plug and the foot lever actuated and the hereinbefore described operation is repeated.

By reason of the arrangement of the cam lug 74 and the lock rod 70, the clutch is 20 disengaged from the constantly rotating gear 62 on the counter shaft 63 after each complete revolution. Thus, for each complete revolution of the counter shaft 63, the cam shaft 53, by reason of the reduction 25 gears 65 and 66, is rotated one-half revolution. This permits the pawl 78 to engage a notch 80 of the locking disk 79, thus locking the cam shaft 53 after each 180 degree rotation and holding the yoke 82 at the end of 30 its stroke. This locking of the cam shaft also locks the counter shaft and holds the lug 74 of the clutch 69 in position behind the weighted stop rod 70.

It is noted that the mechanical expansion 35 of the wall of the cup has a tendency to produce true circularity. It is also noted that, whether the hot cup is mechanically expanded by the plug or not, the tendency of the cup to shrink in quenching causes said 40 cup to conform to the accurately finished surface of the plug and maintain the proper concentricity and taper of the inner or bearing surface of the cup.

The outer surface of the cup may be also 45 restrained during the quenching operation if desired. In case it is desired to grind the outer surface after the cup has been hardened, it is preferable to quench the inner surface before submerging the entire cup. 50 The margin of the block is fluted in a manner similar to the flutes 43 in the tapered ends of the plugs 30 and the bottoms of the flutes have ports that open into a hollow chamber in the middle of the block, which 55 chamber in turn communicates with a suitable source of quenching liquid and means for forcing it through such ports at will. By this arrangement, the inner surface of the cup is subjected to the action of streams 60 of quenching liquid throughout its entire surface except for the intervals between adjacent flutes; and these intervals are sufficiently small to not materially change the concentricity of the surface. After this initial hardening of the inner surface, the whole 65

cup is submerged in quenching fluid as above described.

In the case of cones, the outer surface is the bearing surface and is the one that requires hardening. For the treatment of 70 cones, it is preferable to form the cone with a slightly tapered bore, even if the taper must be subsequently reduced or eliminated to suit the requirements of the finished cone. When the cone is ready for quenching, it is 75 placed over a slightly tapered plug adapted to fit its bore. A die block with conical ribs of the proper taper to bear against the outer surface of the cone is then placed over the cone and maintained in contact therewith during 80 the quenching operation. This die block has a number of ports opening radially in the flutes between ribs, which ports communicate with a suitable source of supply of quenching liquid. Means similar to that shown 85 in the accompanying drawings may be used for controlling the flow of quenching liquid. In operation, the heated cone is mounted on the tapered plug and the outer conical die block is placed over the cone and in contact 90 therewith, and pressure (which may be only the weight of the heavy die block) is maintained throughout the quenching operation. The source of liquid supply is then manipulated so that streams of quenching liquid 95 are sprayed on to the outer surface of the cone except for the narrow spaces covered by the ribs of the die block. Then the entire device is submerged in quenching liquid. On account of the taper of the plug, the cone 100 can be easily removed therefrom, just as it is an easy matter to strip the quenching cup from the tapered block on which it shrinks.

In some instances it may be desirable to 105 form the cups with tapered outer surfaces as well as with tapered inner surfaces. In such case, the hot cup, as it comes from the hardening furnace, is dropped into a tapered die block, preferably of the same taper as the exterior surface of the cup and otherwise adapted for the cup to fit. A conical metal plug of the same taper as that desired for the inner surface of the cup is then forced axially into said cup, whereby the 110 taper of the inner surfaces of the cups is maintained or becomes the same as the taper of the plug, and the inside diameter of the cup will be increased more or less according to the distance the plug is forced through the rings. During the quenching operation, 115 the outer surface of the cup is preferably restrained by its fitting in the taper of the die block, this fit being itself maintained by the tendency of the cup and plug to slip downward in the die block (under pressure 120 or even by their own weight) and thus automatically compensate for any shrinkage of the metal incident to quenching. By the arrangement described, the outer surface of 125 the cup conforms to the taper of the die 130

block and takes the diameter thereof; but it is obvious that the die block may be dispensed with and the tapered plug used alone to give the inner surface of the cup the desired taper and size.

What I claim is:

1. A device for quenching metal rings, said device comprising a stationary holder for a ring and a movable plug adapted to enter the bore thereof and enlarge the same to size, said holder and said movable plug having ports communicating with a source of quenching liquid, and means actuated by said plug for controlling the flow of the liquid to said holder and said plug during the engagement of said plug with the ring, whereby said plug actuates said controlling means and permits the quenching liquid to be directed against the exterior and interior surfaces of the ring through the ports of the respective holder and plug.

2. A device for use in sizing and quenching conical cups which consists of a tapered plug, means for producing relative movement of said plug axially with respect to the cup under treatment, said plug having a portion of its outer surface of the size and taper desired for the inner surface of said cup, and means for bringing said portion of the plug into contact with the inner wall of said cup and keeping them in contact during the quenching operation.

3. A device for use in sizing and quenching cups for conical roller bearings comprising a support for an unfinished cup, a tapered plug movable axially with relation to said cup, and means for limiting the movement of said plug, said plug having a portion in contact with the inner wall of said cup when the plug is at the end of its effective stroke and said portion being of approximately the size and taper desired for said cup.

4. A device for use in quenching hollow conical bearing parts consisting of a tapered inner member and an outer member with a tapered bore conforming to the inner and outer peripheral surfaces respectively of the bearing part to be produced and means for pressing said members towards each other to a predetermined extent for sizing the bearing part between them and for maintaining the relation of such members during the quenching operation.

5. A device for use in quenching cups for conical roller bearings consisting of a conical taper die block adapted to fit the outer surface of the cup and a tapered block adapted to fit the inner surface of the cup, and means for pressing one of said members axially relatively to the other and means for predetermining the relative movement of said members so as to size a cup between them.

6. A device for use in sizing and quench-

ing cups for conical roller bearings comprising an outer member having a conical socket of approximately the size and taper desired for the outer surface of the cup and an inner member concentric with said outer member and relatively axially movable with relation thereto, said inner member having the portion of its outer surface that is in contact with the cup at the end of its effective stroke of approximately the size and taper required for the inner surface of said cup.

7. A device for use in quenching cups for conical roller bearings consisting of a conical taper die block adapted to fit the outer surface of the cup, and a tapered block having longitudinally disposed ribs adapted to fit the inner surface of the cup and inclined with relation to axial planes passing through them respectively.

8. A device for use in quenching cups for conical roller bearings consisting of a conical taper die block adapted to fit the outer surface of the cup, and a tapered block having ribs adapted to fit the inner surface of said cup and having ports in the spaces between ribs communicating with a source of quenching liquid.

9. A device for use in quenching cups for conical roller bearings consisting of a conical taper die block adapted to fit the outer surface of the cup, and a tapered block having ribs adapted to fit the inner surface of said cup and having ports in the spaces between ribs communicating with a source of quenching liquid, and means for submerging said device in quenching liquid.

10. A device for sizing and quenching metal rings and the like, said device comprising a holder for a ring having ports communicating with a source of quenching liquid, a valve controlling the flow of quenching liquid, and a movable plug adapted to enter within the ring in said holder and expand the bore thereof, said plug being arranged to actuate said valve to permit flow of quenching liquid to said holder when said plug completes the expansion of said bore.

11. A device for quenching metal rings, said device comprising a holder for a ring and a movable plug adapted to enter and size the bore of the ring, said holder and said plug having ports adapted to communicate with a source of quenching liquid, and means arranged to be actuated by said plug while in engagement with the ring for permitting the flow of liquid to the ports of said holder and said plugs, whereby the quenching liquid is directed against the interior and exterior surfaces of the ring.

12. A device for quenching hollow metal articles, said device comprising a support for an article and a power actuated plug adapted to enlarge the bore of such article,

and means operated by said plug whereby the flow of quenching liquid is directed against the article when said plug completes such enlargement of the bore and the flow 5 of liquid is stopped when said plug is withdrawn from engagement with said article.

13. A device for quenching metal rings, said device comprising a holder for a ring, a movable plug adapted to enter and size 10 the ring, said holder and said plug having ports communicating with a source of quenching liquid, and means operated by said plug for controlling the flow of the quenching liquid to said holder and said 15 plug.

14. A device for quenching metal rings, said device comprising a stationary holder for a ring and a movable plug adapted to enter the bore thereof and enlarge the same 20 to size, said holder and said movable plug having ports communicating with a source of quenching liquid, and means actuated by said plug for controlling the flow of the liquid to said holder and said plug during 25 the engagement of said plug with the ring, whereby said plug actuates said controlling means and permits the quenching liquid to be directed against the exterior and interior surfaces of the ring through the ports 30 of the respective holder and plug and, when said plug is out of engagement with said ring, the flow of liquid to said holder and said plug is stopped.

15. A device for quenching metal rings comprising a holder for a ring and a vertically operated plug adapted to enter the bore thereof and enlarge the same to size the ring, said holder and said plug having ports formed therein adapted to communicate 35 with a supply of quenching liquid, and control means for normally stopping the flow of quenching liquid to the ports of said holder and said plug, said control means being adapted to be actuated by said plug 40 when in engagement with the ring to permit the quenching liquid to flow through the ports of said holder and said plug and be directed against the exterior and interior 45 surfaces of the ring.

16. A device for quenching metal articles comprising a pair of supports for an article and a pair of movably mounted members adapted to engage said articles in one position of their movement, and spraying devices for directing quenching liquid against the articles on each of said supports, said spraying devices communicating with a source of quenching liquid, and normally closed means for controlling the flow of the 55 quenching liquid from said supply source to said spraying devices, said means being actuated by said movable members when said members are in engagement with the article to permit the flow of liquid to said spraying 60 devices.

17. A device for quenching metal rings and the like comprising a pair of holders adapted to receive a ring and a pair of vertically movable plugs adapted to fit within 70 rings, said holders and said plugs having ports adapted to communicate with a source of quenching liquid, and normally closed control means for controlling the flow of the liquid to each of said holders and each of 75 said plugs, said plugs being adapted to be alternately raised and lowered and each being adapted to actuate the control means when in engagement with a ring to permit the flow of liquid to said holders and said 80 plugs, whereby liquid is directed against the exterior and interior surfaces of said rings.

18. A device for quenching metal rings and the like comprising a pair of holders adapted to receive a ring and a pair of vertically movable plugs adapted to fit within 85 rings, said holders and said plugs having ports adapted to communicate with a source of quenching liquid, and normally closed control means for controlling the flow of the liquid to each of said holders and each 90 of said plugs, said plugs being adapted to be alternately raised and lowered and each being adapted to actuate the control means when in engagement with a ring to permit the flow of liquid to said holders and said 95 plugs, whereby liquid is directed against the exterior and interior surfaces of said rings, and means for automatically stripping the rings from said plugs during the upward movement thereof.

19. A device for quenching metal rings and the like comprising a pair of holders adapted to receive a ring and a pair of vertically movable plugs adapted to fit within 100 rings, said holders and said plugs having ports adapted to communicate with a source of quenching liquid, and normally closed control means for controlling the flow of the liquid to each of said holders and each of 105 said plugs, said plugs being adapted to be alternately raised and lowered and each being adapted to actuate the control means when in engagement with a ring to permit the flow of liquid to said holders and said plugs, whereby liquid is directed against the exterior and 110 interior surfaces of said rings, means for automatically stripping the rings from said plugs during the upward movement thereof, and a receptacle surrounding said holders, said receptacle being adapted to receive the 115 waste quenching liquid from said holders and having a drain pipe adapted to carry away the waste liquid.

20. A machine for quenching metal articles comprising a quenching device adapted to receive an article, a vertically operating plunger adapted to engage the article, means for alternately raising and lowering said plunger, means for automatically stopping said plunger in its raised and lowered 120 125 130

- positions respectively, and a normally closed control means for controlling the flow of liquid to said quenching device, said control means being adapted to be actuated by said plunger when said plunger is in engagement with the article to permit the flow of liquid to said quenching device. 5
21. A machine for sizing and quenching metal rings and the like comprising a table, a quenching device mounted on said table and communicating with a source of quenching liquid, a vertically movable plunger adapted to be forced axially into a ring, a toggle operatively connected to said plunger for raising and lowering the same, a yoke operatively connected to said toggle for actuating the same, a cam for actuating said yoke, means for rotating said cam, and means for automatically locking said cam when the plunger is in raised and lowered positions respectively. 10
22. A machine for sizing and quenching metal rings and the like comprising a table, a quenching device mounted on said table and communicating with a source of quenching liquid, a normally closed control device for controlling the flow of the liquid to said quenching device, a vertically movable plunger adapted to be forced axially into a ring, 15 said plunger being adapted to actuate the control device when in engagement with said ring to permit the flow of liquid to said quenching device, a toggle operatively connected to said plunger for raising and lowering the same, a slidably mounted yoke operatively connected to said toggle for actuating the same to raise and lower said plunger, a rotatable cam for actuating said toggle, continuously operating drive gear- 20 ing, a clutch device for operatively connecting said rotatable cam with said drive gear- 25 ing, means for automatically disengaging said clutch from said drive gearing when the plug is in its uppermost and lowermost positions respectively, and means for automatically locking said cam and said clutch when the plunger is in either its raised or its lowered position. 30
23. A machine for sizing and quenching metal rings and the like comprising a table, a pair of quenching devices mounted on said table and communicating with a source of quenching liquid, a normally closed control device for controlling the flow of the quenching liquid to each of said quenching devices, 35 vertically operating plugs located above each of said quenching devices and adapted to be forced axially into the ring on the respective quenching devices, said plugs being adapted to actuate the control device of the respective holders when in engagement with the rings to permit the flow of liquid thereto, devices on said plugs for automatically stripping the rings therefrom, a double toggle operatively connected to each of said 40 plugs for simultaneously raising one and lowering the other, a slidably mounted yoke operatively connected to said double toggle for actuating the same, a rotatable cam for actuating said yoke, continuously rotating 45 drive gearing for rotating said cam, a normally disengaged clutch member for connecting said drive gearing to said cam, and means for automatically disengaging the clutch means from the drive gearing when 50 the plugs reach their uppermost and lowermost positions, and means for automatically locking said cam and said clutch to hold the plungers in said positions respectively. 55

Signed at Canton, Ohio this 18th day of 30 March, 1920.
